Joel Bryant.

UNITED STATES PATENT OFFICE.

JOEL BRYANT, OF BROOKLYN, NEW YORK.

IMPROVEMENT IN CONSTRUCTION OF FLY-WHEELS.

Specification forming part of Letters Patent No. 40,011, dated September 22, 1863; antedated June 9, 1862.

To all whom it may concern:

Be it known that I, JOEL BRYANT, of Brooklyn, in the county of Kings and State of New York, have invented a new and Improved Mode of Using Fly-Wheels in Connection with Portable Machines; and I declare the following to be a full, clear, and correct description of the same—to wit:

The nature of my invention consists in so constructing portable machines—such as crushing and grinding mills, corn-shellers, turning-lathes, and all other machines to which my said invention is applicable—with fly-wheels set to run beneath the base or bottom part of said machines, as hereinafter described, so as thereby to add to the force, power, and efficiency of said machines, as hereinafter set forth.

To enable others skilled in the art to make and use my invention, I will proceed more fully to describe the construction and operation of machines provided with fly-wheels, and using the same in accordance with my improved mode of using fly-wheels in connection with portable machines, and all other machines to which my said invention is applicable, reference being made to the accompanying drawings, and to the figures and letters marked thereon, and forming a part of this specification—to wit:

Figure 1, M, represents a perspective view of my invention or improved mode of using fly-wheels W, in connection with portable or any other machines, M, whose construction and arrangement of parts admit of the application of my invention thereto.

I construct my machines M (irrespective of kind) with a base or bottom part, B, adapted to receive and hold within or beneath the said base B a fly-wheel, W, set to run on an upright shaft, S, and within or beneath the said base or bottom B, the said upright shaft S being provided with a stop, V, which rests on an anti-friction roller-bearing, G, as shown in Fig. 2, the said anti-friction roller-bearing G being made as shown in Fig. 3, resting in its turn on the upper part of the said base B, thus relieving the working parts of said machines M from the weight of the said fly-wheels W, which run with very little friction, as supported on the bearing G.

Fig. 3 represents and shows the construction of the said anti-friction roller-bearing G, which is made with four anti-friction rollers,

Z, running loosely on their axles A, which are firmly connected with a strong ring, R, which is made of sufficient size to receive the said shaft S and allow it to turn loosely therein. The said anti-friction roller-bearing G, made as aforesaid, turns with the said shaft S, which rests thereon, through the medium of the said stop V, so that the said machines M run with very little friction, whatever may be the size and weight of the said fly-wheels W.

Fig. 4 represents my invention as applied to small-sized grinding-mills M.

Fig. 5 shows the way of connecting the fly-wheels W with the shafts S.

Fig. 6 represents the aforesaid invention modified by the omission of the said anti-friction roller-bearing G, the said shaft S in this case being made to rest and run on ordinary bearings at the bottom part of the said base B of said machines. The said invention may of course be thus modified without materially changing the character of the invention, and, when desirable, I thus modify my said invention or improved mode of using fly-wheels W in connection with portable or other machines M, as shown in Fig. 6.

The advantages of my invention are, that fly-wheels W of any desirable size may be used in connection with any machines M which are adapted to their use, as herein proposed, and the weight and size of the said fly-wheels W may be adapted to the requirements of the said machines M and used in connection therewith with less inconvenience and with better results than in any other known way, adding much to the convenience and utility of said machines.

What I claim as my invention, and desire to secure by Letters Patent of the United States, is as follows, to wit:

The within-described mode of using fly-wheels W in connection with portable or other machines M, Figs. 1, 2, 4, and 6, when the said fly-wheels W are set to run within or beneath the base B of said machines M on anti-friction roller-bearings G, or their equivalent, substantially as herein described, and for the purposes set forth.

JOEL BRYANT.
